Arthur Salm Inc., Chicago, Ill., a corporation of Illinois

Filed Sept. 8, 1959, Ser. No. 57,475

Claims priority, application Italy Mar. 14, 1959

Term of patent 14 years

(Cl. D22—3)

Fig. 1 is a perspective view of a pocket tool kit showing my new design as it appears with the end cap in open position and the scissors partially removed, the broken line showing of the scissors being for illustrative purposes only;

Fig. 2 is a rear view thereof as it appears with the end cap in closed position;

Fig. 3 is a top view thereof;

Fig. 4 is a front view thereof;

Fig. 5 is a bottom view thereof;

Fig. 6 is an end view thereof viewed from the left in Fig. 2; and

Fig. 7 is an end view thereof viewed from the right in Fig. 2.

The dominant feature of my design resides in the pivoted end cap shaped as shown.

I claim:

The ornamental design for a pocket tool kit, substantially as shown and described.
